CLAIM

The ornamental design for an ultrasonic control device for endoscope, as shown and described.

DESCRIPTION

FIG. 1 is a top, front and right side perspective view of an ultrasonic control device for endoscope showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a top, front and right side perspective view thereof in an open position; and,

FIG. 9 is a top, front and right side perspective view thereof in a manner of use.

The broken lines showing the portions in FIGS. 8 and 9 depict environmental subject matter only and form no part of the claimed design.
